[57] CLAIM

The ornamental design for a baby bottle holder, as shown and described.

DESCRIPTION

FIG. 1 is a top, rear and left side perspective view of a baby bottle holder showing my new design, with the fingers in a straight position;

FIG. 2 is a top, rear and left side perspective view thereof, with the fingers in a bent position;

FIG. 3 is a top, front and left side perspective view thereof, with the hand rotated to the left;

FIG. 4 is a top, front and left side perspective view thereof, with the hand rotated to the right;

FIG. 5 is a right side elevational view thereof;

FIG. 6 is a bottom plan view thereof; and,

FIG. 7 is a top plan view thereof.
